ABSTRACT

A shelf has a platform suspended by at least three cords or other flexible suspension means. The upper ends of the cords are gathered in a knot formed with a loop for suspension from a hook. The lower ends of the cords are attached to the platform, two of these cords being attached at, or near, the opposite ends of the side of the platform which, in one use of the shelf, is located near a wall. A slide similar to a bead receives the latter two cords. When the shelf is suspended from a hook located remote from a wall the bead is slid up to the knot and, since the cords are of the same length, the platform is horizontal. If the point of suspension is on or close to a wall, the bead is slid downwards to reduce the straight-line distance between the points of attachment to the platform and the knot. the position of the bead is adjusted so that the platform is horizontal (or at some desired slope).

HANGING SHELF WITH LEVELLING MEANS

This invention relates to a new and improved hanging shelf with levelling means so that the shelf may be suspended from the ceiling or a wall at a horizontal level or at a desired slope.

A principal feature of the present invention is to provide a shelf having a levelling means incorporated in the suspension cord so that the shelf may be alternatively suspended either from the ceiling or from a hook in a wall and the position of the shelf adjusted, regardless of the distance which the hook projects from the wall.

A feature of the invention is the fact that the levelling means insures that the platform of the shelf is horizontal when suspended from any point along an arc of any degree.

A feature of the invention is the fact that the user may hang the shelf from a variety of different locations. Complete mobility is provided in that the shelf may be relocated simply by removing it from one hook and hanging it from another.

Another advantage of the invention is the fact that an adjustable shelf is afforded which can be hung from a wall by only one hook, thus avoiding the use of brackets and nails or screws. Accordingly, little skill, few tools, and a minimum of equipment is required to locate and level the shelf.

Another advantage of the invention is the fact that the shelf may be used as a unique display for plants, curios, art objects, etc. When hung against the wall, with the bead in lowered position, the configuration of the cords suspending the platform create an aesthetically pleasing design which enhances the display.

Another feature of the invention is the fact that instead of hanging the shelf horizontal, it may be tilted at any desired angle so that the articles positioned thereon may be viewed.

Other objects of the present invention will become apparent upon reading the following specification and referring to the accompanying drawings in which similar characters of reference represent corresponding parts in each of the several views.

In the drawings:

FIG. 1 is a perspective view of one form of the device suspended from a hook on the ceiling.

FIG. 2 is a view similar to FIG. 1 showing the hook attached to a wall.

FIG. 3 is an enlarged fragmentary view partly broken away in section of the upper end of the suspension device.

FIG. 4 is a view similar to FIG. 2 showing a modified construction.

FIG. 5 is a fragmentary bottom plan, partly broken away, of the structure of FIGS. 1-3.

Directing attention first to the form of invention shown in FIGS. 1-3, a platform 11 which is preferably rectangular but may be of other shapes is provided. Adjacent each of the four corners is a hole 12. A cord consisting of two flexible strands 13 fits through the front holes 12 and then under the platform 11 in a stretch 13. Preferably, a knot 24 is formed in one strand 13 and force-fit into a hole 12 to prevent the cord from sliding. Similarly, rear strands 16 pass through the rear holes 12 with a similar connecting stretch and knot 17. It will be understood that other means of attachment of the lower ends of the cords 13, 16 may be used.

The upper ends of cords 13, 16 are connected together, preferably so that the cords are of equal length. A preferred means is a knot 18 having an upward projecting loop 19.

Slidable along the rear cords 16 is a bead 21 formed with a bore 22 through which the cords 16 pass. Preferably there is some friction between the cords 16 and the bore 22, and the bead 21 remains in a position of adjustment despite considerable weight being imposed on the platform 11.

Directing attention to FIG. 1, a hook 26 is located in the ceiling at a distance from any wall. Loop 19 is suspended from hook 26. In this form of the invention, assuming that the platform 11 is to be horizontal, the bead 21 is raised to its uppermost position so that an

effective lengths of cords 13, 16 for practical purposes are the same. In FIG. 2, hook 27 is located in a wall. In order to maintain the platform 11 horizontal with the back edge 28 of platform 11 resting against the wall, bead 21 is slid along the cords 16 to a lower position

so that the effective length of cords 16 is reduced. It will be understood that the distance which hook 27 projects from the wall is subject to considerable variation. This variation in distance may be accommodated by moving bead 21 up and down on cords 16 until the shelf 11 is horizontal. It will further be understood that the shelf 11 may be tilted merely by the positioning of bead 21.

Directing attention now to FIG. 4, the platform 11a is of any desired shape other than rectangular but preferably has a straight back edge 31 which fits against the wall. In the form of the invention shown in FIG. 4, only a single front cord 13a is employed rather than two cords 13 of FIG. 1. In other respects, the modification of FIG. 4 is similar to that of the preceding modification and the same reference numerals followed by the subscript *a* are employed to designate corresponding elements. The positioning and adjustment of bead 21a in the modification of FIG. 4 is substantially the same as in the preceding modification. Front cord 13a is attached to platform 11a but knot 14a is under hole 12a.

What is claimed is:

1. In a shelf combination, a platform, at least three cords, the lower ends of said cords attached to said platform at widely spaced-apart positions on said platform to suspend said platform, means joining together the upper ends of each of said cords and having a loop for attachment to a hook or other suspension, and a slider manually slidable along only two of said cords between an upper location and a lower location to adjust the effective lengths of said two said cords to adjust the angle of said platform to the horizontal when said shelf is suspended by said loop, said slider comprising a bead formed with a bore, said two cords extending through said bore, the friction between said two cords and said bore holding said bead in a position of adjustment, said platform being formed with holes at said spaced positions, the lower ends of said cords passing through said holes, and fastened below said platform, said attachment of said cords to said platform being independent of said slider.

2. The combination of claim 1 in which the number of said cords is four and said spaced positions are located at the corners of a rectangle.

3. The combination of claim 1 in which the number of said cords is three and said spaced positions are located at the corners of an isosceles triangle.

4. The combination of claim 1 in which said means joining together said upper ends of said cords is a knot of said cords.
